LATCHING DEVICE FOR VACUUM CLEANERS

Albert William Kandetzki, Stamford, Conn., assignor to Electrolux Corporation, Dover, Del., a corporation of Delaware

Application December 21, 1937, Serial No. 181,017

7 Claims. (Cl. 292—51)

My invention relates to latching devices for closures of vacuum cleaners and more particularly for vacuum cleaners of the type having an enclosed dust bag.

5 In vacuum cleaners of this type it is desirable to remove the dust bag or dust separating member from the vacuum cleaner casing periodically for emptying the dust contained therein. In accordance with my invention, an improved closure member is removably secured to the vacuum cleaner casing; secures the dust bag in position and permits its ready removal and replacement.

10 What I consider to be novel and my invention may be better understood by reference to the following specification and appended claims when considered in connection with the accompanying drawings, in which

15 Fig. 1 is a side view of a vacuum cleaner broken away in part and incorporating my improved closure member;

20 Fig. 2 is a front view of the closure member;

Fig. 3 is a back view of the closure member;

25 Fig. 4 is an enlarged sectional view of the closure member and a portion of the vacuum cleaner;

Fig. 5 is an enlarged rear view of the closure member with the back plate removed;

30 Fig. 6 is a detailed view of a portion of the locking mechanism with the parts shown in different relative positions than the parts of Fig. 5;

Fig. 7 is a detailed view of a portion of the vacuum cleaner end ring;

Fig. 8 is a detailed sectional view taken along the line 8—8 of Fig. 5;

35 Fig. 9 is a detailed sectional view taken along line 9—9 of Fig. 5; and

Fig. 10 is a detailed sectional view similar to Fig. 4 but with the handle in a different position.

40 Referring to the drawings 10 indicates generally a vacuum cleaner of the enclosed bag type in which a cleaning tool 11 is connected to a cleaner unit 12 by means of a flexible hose 13 with or without a substantially rigid tubular member 14. A dust separating member or dust

45 bag 15 is located in the unit 12 and is secured therein by means of a closure member 16. Dust bag 15, as may best be seen by reference to Fig. 4, is provided with a dust bag ring 17 with an outwardly extending flange 18. A compressible 50 gasket 19 of U-shape is snapped over the flange 18.

55 A motor fan unit consisting of a motor 20 and a multistage centrifugal fan 21 produces a flow of air from the front of the cleaning unit 12, shown at the left in Fig. 1, to the rear shown at

the right. The flow of air produced by the motor fan unit draws air in through the cleaning tool 11 which carries with it dust or dirt located on the surface which the cleaning tool 11 contacts. The air passes from the cleaning tool 5 11 through the tubular member 14, flexible hose 13 and through an aperture 22 in the closure member 16 entering the cleaning unit 12. The dirt carried by the air is separated therefrom as it passes through the dust bag 15. The air then 10 continues through the fan 21, motor 20 and out an exhaust opening 23. After a certain amount of dust and dirt has collected in the dust bag 15 it is desirable to remove the dust bag 15 and empty the dirt therefrom. To facilitate the 15 emptying of the dust bag 15 closure member 16 is provided with means for its ready removal and replacement as will be pointed out below.

A hollow dish-shaped casting 24 forms the front surface of the closure member 16 with an 20 opening 25 through which an operating handle 26 extends. The rear of the casting 24 is covered by a back plate 27. Located at opposite sides of back plate 27 are two boss receiving openings 28 into which detents 29 extend. A 25 ring 30 is secured to the casing 31 of cleaner unit 12 by means of screws 32 and has an inwardly extending flange 33 which forms a seat for dust bag ring flange 17 as best indicated in Fig. 4. Ring 30 is provided with forwardly extending bosses 34 which are adapted to enter the boss receiving openings 28 in back plate 27 into a position to be engaged by detents 29. Fingers 35 which carry detents 29 are pivotally secured to a frame plate 36 by means of pins 37. By reference to Fig. 8 it may be seen that the frame plate 36 is mounted on posts 38 and 39 integral with the casting 24 by means of drive screws 40. Detents 29, when in the position indicated in Figs. 3 and 5, enter side pockets 41 provided in bosses 34 and 40 engage inclined surfaces 42 of springs 43. Springs 43 are mounted on integral posts 44 of ring 30. A cover plate 45 is secured to posts 44 together with spring 43 by means of drive screws 46. A bumper 47 of rubber or other flexible material 45 is located between spring 43 and cover plate 45 with a portion extending through an opening in the top of cover plate 45 shown at the left in Fig. 7. Bumper 47 serves to protect the bosses 34 from injury by contact with the closure member 16.

50 Fingers 35 are provided with pinion teeth 48 which are engaged for movement of the detents 29 by the teeth 49 of a sliding rack bar 50. Rack bar 50 is secured to frame 36 by means of two 55

headed pins 51 which extend through slots 52 in the rack bar 50. When the rack bar 50 is in the position indicated in Fig. 5, detents 29 extend outwardly entering the pockets 41 and engaging the inclined surfaces 42 of springs 43. When the rack bar 50 is moved upwardly the fingers 35 are pivoted moving the detents 29 downwardly out from the pockets 41 of bosses 34 to the retracted position indicated in Fig. 6. The movement of the sliding rack bar 50 in this direction is stopped by engagement of the end of slots 52 with the pins 51.

For movement of the rack bar 50 in the direction of the arrows A, from one position to another, turn block 53 is provided and mounted by means of pivot pin 54 and brackets 55 on casting 24. Brackets 55 are secured to casting 24 by means of drive screws 56. Pivot pin 54 is secured to brackets 55 by means of a cotter pin 57. Handle 26 extending out through the opening 25 in casting 24 is connected to the turn block 53. As shown in the drawing, the handle 26 is cast integrally with the turn block 53. A pin 58 is carried by turn block 53 and engages in slots 59 in ears 60 of rack bar 50.

A toggle mechanism 61 is connected between turn block 53 and casting 24 for holding the turn block 53 in one or the other of its extreme positions. A toggle link 62 of toggle mechanism 61 is connected to turn block 53 by a pivot pin 63. Another toggle link 64 is connected to casting 24 by a pivot pin 65 and a bracket 66. Bracket 66 is connected to casting 24 by drive screws 67. A helically wound spring 68 surrounds the two links 62 and 64 and tends to urge them apart.

When the operating handle 26 is in the position indicated in Fig. 4, the rack bar 50 is in the position indicated in Fig. 5 with the detents 29 extending outwardly into engagement with the springs 43 located in the pockets 41 of bosses 34. When the operating handle 26 is moved away from the casting 24 of closure member 16 to the position indicated in Fig. 10 the turn block 53 is rotated in a counter clockwise direction and by means of the pin and slot engagement with rack bar 50 the latter is moved upwardly. This rotates the fingers 35 moving the detents 29 downwardly and out of the pockets 41 of bosses 34. Easy movement of the rack bar 50 by the turn block 53 is assured by two rollers 69 carried on the ends of pin 58. Lateral movement of the pin 58 and rollers 69 is prevented by upturned ears 70 integral with frame plate 36.

In the assembly of the locking mechanism 55 within the casting 24 of closure member 16 the handle 26 and turn block 53 together with the toggle mechanism 61 are secured to the casting 24 by the drive screws 56 and 67. The fingers 35 and rack bar 50 are secured to the frame plate 36. Frame plate 36 is then secured to the casting 24 by means of drive screws 40. An insulating bushing 71 with a metal sleeve 72 and rubber gasket 73 are secured in the aperture 22 by means of screws 74. The back plate 27 is then secured 65 to the rear of casting 24 by a plurality of drive screws 75. The back plate 27 is also connected to the assembly of bushing 71 and sleeve 72 by means of screws 76. The assembly of the closure member 16 is then complete and ready for use. 70 In the operation of the vacuum cleaner 10 dirt and dust is picked up by the cleaning tool 11 which passes through the tube 14 and flexible hose 13 into the vacuum cleaner unit 12. The dirt and dust is separated from the air passing 75 through the cleaning unit 12 by means of the

dust bag 15. The air then continues through the fan 21 and motor 20 and leaves the cleaning unit 12 through the exhaust openings 23. After the cleaning unit 12 has been operating for a while it is advantageous to remove the dust bag 15 and empty the dust collected within it. This may be accomplished by grasping the operating handle 26 of the closure member 16 and moving it away from the casting 24. As the handle 26 is moved in this direction the turn block 53 is rotated in a counter clockwise direction against the bias of spring 68 of toggle mechanism 61. When the turn block 53 rotates pin 58 in a counter clockwise direction the pin 58 and rollers 69, in engagement with the slots 59, move the rack bar 50 upwardly. Due to the movement of the rack bar 50 upwardly the fingers 35 are pivoted about the pins 37 and detents 29 moved downwardly out of the pockets 41 of bosses 34. When the detents 29 have been moved to the fully retracted 20 position, the closure member 16 may be removed from the ring 30 by continued movement of the hand grasping the operating handle 26 in the same general direction in which it is moved to release the detents 29. The dust bag 15 may 25 then be removed from the casing 31 of the cleaning unit 12.

After the dust bag 15 has been emptied it may be replaced within the casing 31. The closure member 16 is then replaced on the ring 30 by 30 grasping the handle 26 which is in the open position, or if not in this position should first be moved to the open position. The closure member 16 is then placed on the ring 30 with the bosses 34 entering the boss receiving openings 28 of back plate 27. After the closure member 16 is seated in position on the ring 30, the handle 26 is moved toward the casting 24. As the handle is moved in this direction the turn block 53 is rotated in a clockwise direction against the bias of spring 40 68 of toggle mechanism 61. The rack 50 is moved downwardly through the interconnection of the pin 58, carried by turn block 53, and slots 59 and the ears 60. As the rack bar 50 moves downwardly, the fingers 35 are pivoted moving the 45 detents 29 upwardly. The detents 29 enter the pockets 41 of bosses 34, and engage the inclined surfaces 42 of springs 43 producing a force in a direction to compress the dust bag ring gasket 19 between the seat provided by flanges 33 of ring 30 50 and the back plate 27 of closure member 16. The detents riding on the inclined surfaces 42 also produce a force which holds the closure member 16 in its proper position on the bosses 34. When the operating handle 26 has been 55 moved to the fully closed position the turn block 53 and rack bar 50 together with the detents 29 are held in the closure engaging position by the toggle mechanism 61. When the closure member 16 is removed from the ring 30 and replaced 60 on it, it is unnecessary to disconnect the flexible hose 13 from the aperture 22 as it may be moved with the closure member 16.

What I claim is:

1. A latching mechanism including a hollow 65 dish-shaped member, a handle extending outwardly through an opening in said member, a turn block connected to said handle, a bracket secured within said member for pivotally mounting said turn block, a toggle mechanism connected between said turn block and said member, a frame secured to said member, pivoted fingers carried by said frame, a sliding rack secured to said frame for moving said fingers upon movement of said turn block, and a back plate secured 70 75 to said frame.

to said member having openings adapted to receive bosses for engagement by said fingers.

5. 2. In a latching mechanism a member having an opening, brackets secured to said member at opposite sides of said opening, a handle extending through said opening, a pivot pin securing said handle for rotary movement on said brackets, a toggle mechanism, a pin connecting one side of said toggle mechanism to said handle, a 10 bracket secured to said closure member, a pin connecting the other side of said toggle mechanism to said bracket, a frame secured to said hollow member, a sliding rack secured to said frame and having upstanding ears, a pin secured to said handle and engaging said ears, fingers pivotally secured to said frame and engaged by said rack, and a cover plate secured to said member having openings for receiving bosses for engagement by said fingers.
- 15 20. 3. A latching mechanism including a hollow dish-shaped member having an opening, a turn block pivotally mounted on said member, a handle connected to said turn block extending through said opening, a toggle mechanism connected between said member and said turn block, a frame, two fingers pivotally secured to said frame, a sliding rack secured to said frame for moving said pivot fingers, and a pin carried by said turn block and engaging said sliding 25 rack whereby movement of said handle is transmitted to said fingers.
- 25 30. 4. A latching mechanism including a hollow member, a turn block pivotally secured within said hollow member, a handle connected to said turn block, a toggle mechanism connected between said turn block and said hollow member, a frame secured to said hollow member, a pivoted finger carried by said frame, a sliding rack engaging said pivot finger, a pin carried by said turn block loosely engaging said sliding rack, and a back plate secured to said hollow

member having an opening for receiving a boss to be engaged by said pivot finger.

5. 5. A latching mechanism including a hollow dish-shaped casting having an opening, brackets mounted at each side of said opening, a turn block, a pivot pin mounting said turn block for rotary movement on said brackets, a handle extending through said opening and engaging said turn block, a frame plate rigidly secured to said casting, a sliding rack carried by said frame plate having upstanding ears, pivot fingers carried by said frame plate and engaging said rack, said fingers adapted to engage bosses extending from said casting, and a pin carried by said turn block and engaging the ears of said 10 rack for moving the rack from one extreme position to another.

6. 6. In a latching mechanism including a supporting member, a frame plate secured to said member; a sliding rack and pivot fingers carried by said frame plate; a handle secured to said member, extending through an opening therein, and engaging said rack to move said fingers from a latching position to a retracted position and vice versa, and a back plate for said 20 member.

7. 7. In a latching mechanism including a hollow dish-shaped casting, a frame plate, a sliding rack carried by said frame plate having upstanding ears, fingers pivotally carried by said frame plate 30 engaging said sliding rack, a handle extending through an opening in said casting, a pin carried by said handle loosely engaging the ears of said sliding rack, said frame plate having ears extending along the sides of the ears of said 35 sliding rack preventing lateral movement of the pin carried by said handle, a toggle mechanism connected between said casting and said handle, and a back plate for said casting.

ALBERT WILLIAM KANDEZKI. 40
